ATTORNEYS.

UNITED STATES PATENT OFFICE.

JOHN SCHUMACHER, OF LOS ANGELES, CALIFORNIA.

REENFORCED PLASTER BOARD.

Application filed July 24, 1924. Serial No. 727,867.

To all whom it may concern:

Be it known that I, JOHN SCHUMACHER, a citizen of the United States, and resident of Los Angeles, in the county of Los Angeles, State of California, have invented new and useful Improvements in Reenforced Plaster Board, of which the following is a specification.

This invention relates to a reenforced plaster board or the like formed of a cementitious core covered by a pliable sheet. Such products are subjected to rough usage in manufacture, and handling during transportation and during installation in building structures. The edges of such board are especially susceptible to damage and injury due to strains placed thereon, resulting in chipping, cracking and crushing. Reinforcement of the edges is desirable in order to prevent such damage and injury. Such reinforcement should be in all directions, should not detract from the resiliency of the board, should not add to its weight, or materially change the constituent parts of the board. Furthermore, the character of the reinforcement should be such as to make the board economical to manufacture. Another desirable feature to be attained is a reinforcement producing with the other constituents a unitary structure. The primary object of this invention is the provision of a reenforced plaster board or the like, having the aforementioned characteristics.

These objects together with other objects and corresponding accomplishments are obtained by means of the embodiment of my invention illustrated in the accompanying drawing, in which:

Fig. 1 is a perspective view of a fragment of plaster board formed in accordance with my invention; and Fig. 2 is a plan view.

Referring more particularly to the drawing, the plaster board comprises a cementitious core 3 preferably formed of gypsum plaster mixture and pliable covering sheets 4 and 5 preferably formed of paper. The paper and plaster is of such character that they cohere and are firmly bound together. This may be accomplished by means now well known in the art. Interposed in the edge of the board between the covering sheets is a reinforcement strip 6. This reinforcement strip is preferably of the same material as the covering sheets and is embedded in the plaster body. The reinforcement strip

is corrugated and the undulations extend preferably from the upper covering sheet to the lower covering sheet.

The finished product is provided with reinforcement in directions across the thickness of the board as well as along the length of the board. The reinforcement is so distributed that the edge is strengthened in every direction. It is obvious that the resiliency of the board is not detracted from nor its weight added to or its unitary structure changed.

The character of the construction lends itself to easy continuous manufacture as described in a copending application for method of forming plaster board Serial No. 727,868, filed July 24, 1924.

What I claim is:

1. A reenforced plaster board or the like comprising a cementitious body, a covering sheet bound thereto, and a narrow corrugated strip embedded in the edge of said body and bound thereto, said strip extending the length of said board and forming a marginal reenforcement.

2. A reenforced plaster board or the like comprising a cementitious body, a covering sheet bound thereto, and a narrow corrugated strip embedded in an edge of said body and bound thereto, said strip extending the length of said board and forming a marginal reenforcement, the undulations thereof extending substantially the full thickness of said body.

3. A reenforced plaster board or the like comprising a cementitious body disposed between covering sheets and bound thereto, and a narrow corrugated strip embedded in the edge of and bound to said body and extending the length of said board so as to form a marginal reenforcement.

4. A reenforced plaster board or the like comprising covering sheets, a cementitious body disposed between said covering sheets and bound thereto, and a narrow corrugated strip embedded in the edge of and bound to said body, the undulations of said strip extending substantially from one covering sheet to the other, said strip extending the length of said board and forming a marginal reenforcement.

In witness that I claim the foregoing I have hereunto subscribed my name this 18th day of July, 1924.

JOHN SCHUMACHER.
